ABSTRACT OF THE DISCLOSURE

In the process for electrically hydrodimerizing acrylonitrile, the improvement which comprises separating an electrolyte effluent containing an electrolytic supporting salt, acrylonitrile, adiponitrile and electrode reaction-impairing materials into oily and aqueous layers, removing the electrode reaction-impairing materials contained in the oily layer and recycling the resulting oily phase thus purified to the electrolyte.

BACKGROUND OF THE INVENTION**(1) Field of the invention**

This invention relates to a process for electrolytically hydrodimerizing acrylonitrile (called AN hereinbelow) wherein the electrolyte is separated into oily and aqueous layers, electrode reaction-impairing materials are removed from the oily layer and the resulting purified oily layer thus purified is recycled to the electrolyte while conducting the electrolysis.

(2) Description of the prior art

A number of processes have heretofore been known of hydrodimerization of AN. For example, the electrolysis using a homogeneous solution as the electrolyte is disclosed in U.S. Pats. 3,193,477, 3,193,480 and 3,193,481 and use of an emulsion as the electrolyte is disclosed in Belgian Pats. 699,926 and 699,928. Another process is described in Belgian Pat. 684,436. Methods for the recovery of adiponitrile (called ADN hereinbelow) from the electrolyte resulted from these electrolytic processes are known in U.S. Pat. 3,267,131 using a homogeneous solution as the electrolyte and Belgian Pat. 706,573 using an emulsion as the electrolyte.

However, these processes are disadvantageous in that the electrolysis, when carried out over a long period of time, is associated with gradually increasing formation of by-products particularly of propionitrile (called PN hereinbelow) to reduce the yield of ADN on the basis of AN consumed. It is also disadvantageous in these processes that polyacrylonitrile or degenerated products thereof tend to deposit upon the surface of the cathode. In order to overcome these disadvantages methods such as those described in U.S. Pat. 3,335,162, Belgian Pat. 981,980, Netherlands Pat. 651,550 and Belgian Pat. 716,095 have been devised. For example, an attempt is made in U.S. Pat. 3,335,156 of removal of the electrode reaction-impairing materials by removing deposits of partially hydrolyzed polyacrylonitrile formed in the interface after the catholyte is allowed to stand for separation. However, even with these attempts, tendencies for the by-products to be gradually accumulated during the production of ADN for a sufficiently long period of time to reduce the yield of ADN as well as for the polymers to be attached are hardly avoidable.

Even if a catholyte is prepared prior to the electrolysis

2

from freshly purified AN, electrolytic supporting salt and other additives used for the electrolysis while the electrode reaction-impairing materials are removed, it is difficult to maintain the yield of ADN higher than 90% on the basis of AN consumed during the electrolysis conducted for a long period of time, for example, over more than 400 hours. This is especially remarkable with the process operated on an industrial scale wherein every long term operation is not accompanied by the adjustment of the catholyte but just by the removal of the agglutinates on the surface of the cathode. Under such circumstances, maintenance of the yield of 80% over 400 hours necessarily becomes difficult even if the yield of ADN from 85 to 90% is achieved in the initial 400 hours. The fact, which is supported, for example, by the experiment described hereinbelow in comparative Example 2, implies that reduction in the yield of ADN is caused not only by agglutinate degenerated polyacrylonitrile upon the surface of the cathode but also by electrode reaction-impairing materials increasingly accumulated in the electrolyte.

SUMMARY OF THE INVENTION

It is an object of this invention to provide a method of preventing by-production of PN promoted by electrode reaction-impairing materials and reduction in the ratio of forming ADN with passage of time during a long operation by successively eliminating the electrode reaction-impairing materials accumulated in the electrolyte from the system through purification of the oily layer separated from the electrolyte. Another object is to provide a method of successively eliminating electrode reaction-impairing materials from the system by purifying the oily layer separated from the electrolyte while extracting the electrode reaction-impairing materials in the aqueous layer separated from the electrolyte by adding additional ADN thereto, followed by recycling the resulting purified aqueous layer to the cathode, thereby preventing by-production of PN promoted by the electrode reaction-impairing materials and reduction in the yield of ADN during a long operation. Other objects will be apparent from the descriptions hereinbelow.

We have found that the rate of by-production of PN can be remarkably reduced and the yield of ADN increased, as well as the agglutinates on the surface of the cathode can be substantially reduced to a negligible degree thereby enabling stable electrolysis for a long period of time by separating the electrolyte into oily and aqueous layers and successively eliminating the electrode reaction-impairing materials contained in the oily layer out of the system by means of adsorption on a cation exchange resin, extraction with an aqueous acid solution, or extraction from the catholyte by addition of ADN. This invention is based upon the above findings. According to a more preferable embodiment of the invention, while conducting purification of the oily layer in such a method as set forth above, the purification of the aqueous phase is also carried out by adding ADN to the aqueous layer to transfer the electrode reaction-impairing materials contained in the aqueous layer into the oily layer comprising ADN, the remaining aqueous layer is recycled to the catholyte and said oily layer enriched with the materials is purified by means of cation exchange resin treatment, extraction with an aqueous acid solution or distillation followed by recycling for re-use for the same purpose. Thus further reduction in the by-production of PN as well as further increase in the yield of ADN was facilitated.

The method of the present invention can be applied to any of the electrolytes obtained by known electrolytic processes, as well as of the liquids obtained in the course of separation of ADN from the electrolyte, for example,

liquids from separation of AN and PN from the electrolyte.

DESCRIPTION OF THE INVENTION

As the electrode reaction-impairing materials are mentioned reduction products of nitriles and hydrolysis products of nitriles, cyanoethylated products of ammonia such as, for example, β -aminopropionitrile and iminodipropionitrile and the hydrolysis products thereof, cyclization products of ADN such as, for example, those described by O. E. Thompson in J. Amer. Chem. Soc. 80, 5483 (1963) and hydrolysis products thereof, decomposition products of quaternary ammonium salts and the like.

In carrying out the method of this invention, the electrolyte containing AN, ADN and an electrolytic supporting salt is continuously or intermittently drawn out as the electrolysis progresses and separated into oily and aqueous layers by the use of a method described in U.S. Pat. 3,267,131 wherein water and AN is added to a homogeneous solution, a method described in Belgian Pat. 706,573 wherein an emulsion is treated or of a oil separation device, for example, "Coalescer" (trade name) manufactured by Nippon Filter Industries Co., Ltd. The oily layer contains less water and electrolytic supporting salt and more ADN, AN, 2-cyanoethyladiponitrile and PN, whereas the aqueous phase, contrary to the oily layer, contains more electrolytic supporting salt and water.

It is preferable during the separation to maintain pH of the aqueous phase separated between 5 and 11 because of tendency for the basic electrode reaction-impairing materials to be more transferable into aqueous layer under acidic condition and into oily layer under the alkaline condition. At pH higher than 11, by-products such as bis-cyanoethyl ether will be formed with unfavorable results. Adjustment of pH is preferably made by adding a hydroxide comprising the cation of the electrolytic supporting salt or an acid comprising the anion of the same, but is not restricted by the above-mentioned. When the electrolysis is carried out in an electrolyzer with a cathode chamber and an anode chamber divided by a cation exchange membrane, pH of the outlet liquid of the electrolyzer is usually higher than that of the inlet liquid due to a small anion transportation of the cation exchange membrane and naturally the concentration of electrode reaction-impairing materials is higher in the outlet liquid. In this respect, the electrolyte to be subjected to purification is preferably the outlet liquid of the electrolyzer.

As the means by which the electrode reaction-impairing materials are eliminated there is mentioned the treatment of the separated oily layer with a cation exchange resin for removal by adsorption of the impairing materials. Although, the cation exchange resin may be either a strongly acidic resin or a weakly acidic resin, those of H-form or the form of the cation of the salt of the electrolytically supporting salt is preferable. In general, the lower the degree of crosslinkage of the resin (content of divinylbenzene contained in the resin), the superior are both the rate of exchange and the capacity of adsorption, whereas the inferior are the mechanical properties due to great physical changes such as swelling and shrinkage. Accordingly, it is recommended that a porous resin or MR resin (macro reticular structure resin), for example, Amberlite-200 manufactured by Rohm and Haas is used. The amount of resin used is from 0.3×10^{-2} to 2 ml./ampere·hour (abbreviated a·hr. hereinbelow) in terms of the acid form. Regeneration of the resin is effected by conventional procedures.

Another means for eliminating the electrode reaction-impairing materials is the extraction of the separated oily layer with an aqueous acid solution. The aqueous acid solution may be of a strong acid, weak acid or acid salt and is preferably a solution having a pH of 5-1 of the anion forming the electrolytic supporting salt. The extraction is made using a packed column, sieve tray or the like and the amount of aqueous acid solution employed

is preferably from 0.05 to 5 times as much as the oily layer. Recovery of ADN and AN is also conducted by extraction thereof with a by-product PN or another organic solvent. Another method of purification of the oily layer, which is a more preferable embodiment, involves, while carrying out the purification of the oily layer, adding ADN to the aqueous layer separated to transfer the electrode reaction-impairing materials into the ADN, then separating the ADN layer and the aqueous layer, recycling the aqueous phase to the catholyte and purifying the ADN layer by distillation for re-use for the same purpose. Removal of the electrode reaction-impairing materials from both the oily and aqueous layers reduces the amount of the electrode-reaction impairing materials in the catholyte to substantially negligible amount whereby the electrolysis under better conditions becomes feasible. Reduction of by-production of PN and increase in the yield of ADN can be thus achieved. In addition, in any of the above-mentioned, addition of ADN purified by such a means as distillation prior to separation of the electrolyte into oily and aqueous layers enables removal of the electrode reaction-impairing materials in a larger amount from the aqueous layer, due to the fact that the electrode reaction-impairing materials are soluble in ADN and contact of a large amount of oily layer with the aqueous phase enables the better distribution of the electrode reaction-impairing materials into the oily layer. Addition of AN in place of the ADN will increase AN concentration in the aqueous layer too much with the result that by-production of 2-cyanoethyladiponitrile, bis-cyanoethyl ether, polyacrylonitrile and the like will be increased to adversely affect the stable production of ADN in a high yield for a prolonged period of time. It is therefore unfavorable for the desired transfer of the impairing materials in a satisfactory amount into the oily layer.

The oily layer with the electrode reaction-impairing materials removed, which is then recycled to the electrolyte, is preferably purified as frequently as possible. In order to maintain the yield of ADN on the basis of AN consumed over 80% for a long period of time it is at least necessary to keep the alkali value below 30. It is accordingly preferable to purify and recycle the oily layer continuously or intermittently at a rate from 0.5 to 50 ml./a·hr. At rates higher than 50 ml./a·hr. economy will be a burden, though the yield of ADN can be maintained high. Alkali value, as used herein, is the amount of alkali in milliequivalent/l. required for raising pH from 5 to 11 of the electrolyte following purge with nitrogen at pH 3 to remove carbon dioxide subtracted by the value with a fresh electrolyte containing no electrode reaction-impairing materials at an equal concentration, which is taken as being quantitatively indicative of electrode reaction-impairing materials.

As the electrolyzer used for the hydroelectrolytic dimerization of AN there may be used either an electrolyzer divided by a diaphragm into an anode chamber and a cathode chamber or one without diaphragm. The former is preferred however. Either a neutral diaphragm or one selectively permeating cations may be used as the diaphragm. The latter is preferable.

The cathode is made of a material with a high hydrogen overvoltage such as mercury, lead, zinc or cadmium, preferably of lead or lead alloy.

The electrolyte is a homogeneous solution or an emulsion containing AN, ADN and by-products therewith, an electrolytic supporting salt and additives effective for the electrolysis such as a polymerization inhibitor and an emulsifier. As the electrolytic supporting salt are generally used electrolytic salts represented by the general formula

wherein R_1-R_4 is alkyl containing from 1 to 4, preferably from 2 to 3 carbon atoms and X is sulfate, alkyl-

sulfate of the general formula RSO_4^- wherein R is alkyl containing 1-4 carbon atoms or aryl sulfonate of the general formula

wherein R is alkyl containing 0-2 carbon atoms. Other anions that may be used as effective for the hydrodimerization are halogen, nitrate, phosphate and the like.

Although any anolyte may be used in the divided cell provided with a diaphragm, those which produce little adverse effects upon corrosion resistance of the anode and the electrolytic hydrodimerization and are inexpensive are preferable. Especially preferred is sulfuric acid.

The electrolyte is passed through the electrolyzer at a flow rate from 1 to 500 cm./sec., preferably from 10 to 200 cm./sec. while maintaining the pH between 3 and 10. The temperature at which the electrolysis is conducted is preferably from 0 to 70° C. and the current density is 1-100 a./dm.², preferably 5-30 a./dm.².

DESCRIPTION OF PREFERRED EMBODIMENTS

This invention is described in more detail with reference to flow sheets in the accompanying drawing. However, it is to be understood that the invention is not limited to the embodiments as indicated by the drawing. The flow sheet of FIG. 1 shows the electrolyzer in which the electrolytic hydrodimerization is carried out and the circulation system of the cathode and anode. In FIG. 1 the electrolyzer 1 is composed of the cathode chamber 5 and the anode chamber 6 partitioned by the cation exchange diaphragm 7. The anolyte is circulated between the anode chamber and the anolyte tank 3. The catholyte, which is a homogeneous solution or an emulsion containing AN, ADN, an electrolytic supporting salt and other additives, is circulated between the cathode cell and the catholyte tank 2. Temperature of the catholyte is controlled by the heat exchanger 4. FIG. 2 indicates the recovery step which involves separation of the catholyte into oily and aqueous layers, removal of PN and water and separation of ADN. In cases where the catholyte is an emulsion the catholyte is drawn from the catholyte tank 2 and separated into oily and aqueous layers in the separation column 8. The oily layer drawn out of the top of the separation column is passed to the AN stripper 9 in which low-boiling substances such as AN, PN and water are removed and high-boiling substances mainly composed of ADN are drawn out through the nozzle 14. The oily layer drawn out from the nozzle 14, which is free from low-boiling substances is passed to the purification step. The aqueous layer drawn out from the bottom of the separation column 8 is subjected in the water stripper 10 to removal of low-boiling substances mainly composed of water and then returned to the catholyte tank 2. The low-boiling substances distilled out in the AN stripper 9 and the water stripper 10 are collected in the decanter 11 in which distillate mainly composed of AN and PN and one mainly composed of water are separated. The former distillate is passed from the top of the decanter 11 to the PN stripper 12 through which PN is separated from the bottom nozzle 15. The distillate mainly composed of water is passed from the bottom of the decanter 11 to the water stripper 13, through which water is separated from the bottom nozzle 16. The distillates obtained from the PN stripper 12 and the water stripper 13 are recovered in the catholyte tank. Separation in cases where the catholyte is a homogeneous solution is carried out by first admixing a mixture of the distillate mainly composed of AN and PN and one mainly composed of water at an appropriate proportion through the pipe 20 with the catholyte prior to entering into the separation column to a heterogeneous solution, which is subsequently separated into oily and aqueous layers. The nozzle 17 is employed for supplying AN in accordance with the decrease of AN

due to the conversion to ADN. Addition of ADN, if required, is made through the nozzle 20 in the same way as with separation of the homogeneous solution. FIGS. 3 and 4 show the purification step for carrying out the method of the present invention. Referring to the flow sheet on FIG. 3, which shows treatment of the oily layer with a cation exchange resin following separation of the catholyte into oily and aqueous layers, the catholyte drawn out of the catholyte tank 2 is mixed with an acid or alkali introduced through the nozzle 26, pH being adjusted to a predetermined value and then passed to the separation column 8. The aqueous layer thus separated is neutralized with an alkali or acid introduced from the bottom of the separation column 8 through the nozzle 27 to pH of the catholyte and subsequently passed through 21 to the water stripper 10. The oily layer is drawn out from the top of the separation column 8, a part of which is led to the AN stripper 9 (not shown) and the rest is sent to cation exchange column 18 where the material is removed by the adsorption. The resultant effluent is then recycled to the catholyte tank 2. As occasion demands during the treatment the cation exchange resin is regenerated with a regenerating solution stored in the tank 19 and then washed with pure water introduced through the nozzle 21. The cation exchange column, which is operated batchwise according to the drawing, may be operated in a continuous manner. The nozzle 25 is an outlet for the outflow during regeneration.

Referring to the flow sheet on FIG. 4, which shows 30 countercurrent extraction of the acid phase after separation of the catholyte into oily and aqueous phases, using an aqueous acid solution, the pH of the catholyte drawn out from the catholyte tank 2 is adjusted to a predetermined value by adding an acid or alkali introduced through the nozzle 26 and the treated catholyte is passed to the separation column 8. The aqueous phase separated is neutralized with an alkali or acid introduced through the nozzle 27 to a pH of the catholyte and passed through 21 to the AN stripper 9 (not shown). The rest of the oily 40 phase is passed to the extraction column 28 through the bottom thereof filled with Raschig rings and extracted with an aqueous acid solution in a countercurrent manner therein. The oily phase withdrawn from the extraction column 28 is passed to the catholyte tank 2. The aqueous acid solution withdrawn from the extraction column 28 45 is drawn out through the nozzle 31 and treated with an appropriate organic solvent such as PN, methylene chloride or benzene to recover ADN and AN.

Example 1

An electrolyzer having a cathode chamber and an anode chamber each 10 cm. x 10 cm. x 1 mm. in size, equipped with a cathode of lead alloy containing 6% antimony and an anode of lead alloy containing 0.7% silver and 6% 55 antimony, each having an effective area of electrode surface of 10 cm. x 10 cm., partitioned by a cation exchange diaphragm 1 mm. in thickness was used. Using an experimental apparatus as shown in FIGS. 1-3, 2 N aqueous sulfuric acid as an anolyte was circulated at a flow rate 60 of 200 ml./sec. and as a catholyte an emulsion consisting of a 8:2 by volume mixture of aqueous layer consisting of 2% AN, 6% ADN, 8.0% tetraethylammonium sulfate, 0.05% emulsifier and the balance of water and an oily layer containing 17% AN, 75% ADN, 5% water and 65 3% by-products mainly composed of 2-cyanoethyl adiponitrile and PN, pH being adjusted to 8, was circulated at a flow rate of 200 ml./sec. The electrolysis was carried out at a liquid temperature of 50° C. at an electric current density of 10 a./dm.². The catholyte effluent was passed 70 to the separation column 8 where it is separated by means of a settling separator (not shown) into an aqueous layer and an oily layer, the latter being sent to the AN stripper 9 and the rest of the oily layer continuously passed through a cation exchange resin column at a flow rate of 75 200 ml./hr. and then returned to the catholyte tank 2. As

the cation exchange resin there was used 1.5 l. of Amberlite IR-200 of H-form manufactured by Rohm and Haas. The aqueous layer separated was passed to the water stripper 10. After a 1500 hours' continuous operation the yields of ADN and PN on the basis of the AN consumed and the alkali value are as follows:

	ADN	PN	Alkali value
100 hours.....	92	5.5	6.0
1,000 hours.....	90	7.0	8.3

The results were quite satisfactory in view of the fact that the surface of the cathode on completion of the electrolysis had agglutinates adhered in amount less than $\frac{1}{50}$ as much as those observed in the electrolysis without the above-mentioned treatment.

Comparative Example 1

The electrolysis was carried out in the same way as in Example 1 except that no treatment with the cation exchange resin was applied. The results are shown below.

	ADN	PN	Alkali value
250 hours.....	91	6.0	7.2
1,000 hours.....	75	20.3	37.2

The operation was terminated after 1160 hours because of much agglutinates adhering upon the surface of the cathode.

Example 2

An electrolysis was carried out on, as catholyte, a homogeneous solution containing 12% AN, 10% ADN, 35% tetraethylammonium p-toluenesulfonate and the balance of water. A portion of the catholyte was mixed with AN, PN and water recovered from the decanter 11 to a heterogeneous solution, which was treated with tetraethylammonium hydroxide to adjust pH of the aqueous phase to 9. Then the resultant mixture was allowed to stand in the separation column 8 for separation. The aqueous layer separated was neutralized with p-toluenesulfonic acid and passed to the water stripper 10. The oily layer was passed to the AN stripper 9 and the balance was continuously passed through a cation exchange column and then returned to the catholyte tank 2.

As the cation exchange resin there was used 20 l. of Dowex 50WX-4 in acid form manufactured by Dow Chemical. A 1500 hours' continuous operation was carried out in the same experimental conditions as in Example 1 except for the above. The yields of ADN and PN on the basis of the AN consumed were as follows:

	ADN	PN
300 hours.....	90	7.0
1,500 hours.....	88	9.4

At the end of the operation, the amount of agglutinates which adhered on the surface of the cathode was observed to be slightly more than those in Example 2.

Comparative Example 2

An electrolysis was carried out in the same way as in Example 2 except that no treatment with the cation exchange resin was conducted while the electrolyzer was disassembled every 400 hours to clean the surface of the electrode. Results are shown below.

	ADN	PN
1st run..... 400 hours.....	90	7.5
2d run..... 800 hours.....	86	8.7
3d run..... 1,130 hours.....	78	14.3
4th run..... 1,340 hours.....	71	19.1

Following the third run, further 400 hours' continuous operation of electrolysis was unfeasible due to the polymeric material agglutinated upon the surface of the elec-

trode. The table indicates that the yield of ADN decreased due to the material accumulated in the catholyte even with the cleaning of the surface of the electrode.

Example 3

Referring to FIG. 4, the extraction column 28 was filled with Raschig rings and the separation column 8 was an oil-separation tube (Coalescer). A portion of the catholyte was separated into an aqueous layer and an oily layer with pH of the aqueous layer adjusted to 10 with tetraethylammonium hydroxide. Thus separated aqueous layer was neutralized with an aqueous sulfuric acid and then passed to the water stripper 10 while the oily layer was passed through the AN stripper 9 to the extraction column. To the top of the extraction column 28 was supplied the aqueous sulfuric acid of pH=2, and from the bottom was supplied the oily layer in the ratio of 5:1, the countercurrent extraction taking place between them. A portion of the treated oily layer was then passed to the purification step and the balance to the catholyte tank 2. The aqueous sulfuric acid solution enriched with electrode reaction-impairing materials was in turn extracted with PN and the layer containing AN, PN and ADN was sent to the AN stripper. Results of a 1500 hours, continuous operation under the same conditions as in Example 1 except for the above are shown below with reference to the yields of ADN and PN on the basis of the AN consumed.

	ADN	PN
160 hours.....	91	6.0
1,500 hours.....	89	7.8

The condition of the surface of the cathode on completion of the electrolysis was similar to that as observed in Example 1.

Example 4

The whole process was run according to the flow sheet shown in FIG. 2 except that a portion of the catholyte was not passed to the separation column but directly sent to the water stripper 10, in which low-boiling substances such as AN, PN and water were distilled out. To the resulting liquid, after being cooled, was added ADN at a rate of 100 ml./hr. Then to the resulting mixture was added tetraethylammonium hydroxide to adjust pH of the aqueous phase obtained after separation to 10, and the whole was mixed. The resulting mixture was allowed to stand in the separation column 8 for settling and the separated oily layer was passed through a cation exchange column at a rate of 250 ml./hr. for purification, treated effluent being recycled for re-use. The separated aqueous layer was neutralized with sulfuric acid and then passed to the catholyte tank 2. Results of a 1500 hours' continuous operation under the same experimental conditions as in Example 1 except for the above are shown below with reference to the yields of ADN and PN on the basis of the AN consumed.

	ADN	PN
400 hours.....	90	7.3
1,500 hours.....	87	9.1

Upon completion, the agglutinates which adhered to the surface of the cathode was less than those observed in Example 1.

Example 5

The example shows an electrolysis accompanied by the addition of ADN to the catholyte effluent and cation exchange of the oily layer separated from it. A portion of the catholyte, prior to entering into the separation column 8, was subjected to addition of ADN at a rate of 100 ml./hr. and tetraethylammonium hydroxide and subsequently to separation into oily and aqueous layers by the use of an oil-separation tube (Coalescer). The aqueous layer separated, pH 10, was neutralized with sulfuric

acid and then passed to the water stripper 10. A portion of the oily layer was passed to the AN stripper 9 while the rest was passed through the cation exchange column 18, giving purified liquid, which was then recycled to the catholyte tank. Thus, the alkali value in the catholyte was maintained below 10. As the cation exchange resin there were used 3.0 l. of Amberlite IRC-84 of tetraethylammonium form. Results of a 1500 hours' continuous operation under the same experimental conditions as in Example 1 are shown below with reference to the yields of 10 ADN and PN on the basis of the AN consumed.

	ADN	PN
200 hours.....	92	4.9
1,500 hours.....	90	6.0

The agglutinates on the surface of the cathode on completion of the electrolysis were less than those in Example 1.

Example 6

The example shows an electrolysis on a catholyte containing a different electrolytic supporting salt, in an undiaphragmed electrolyzer, while adding ADN to the electrolyte effluent and extracting the oily layer. As the electrolyte there was used an emulsion prepared at pH 7 from an 8:2 by volume mixture of an aqueous layer consisting of 1% tetraethylammonium acid phosphate, 20% sodium acid phosphate, 2% AN, 2% ADN, 4% ADN, 0.05% emulsifier and the balance of water and an oily layer consisting of 17% AN, 75% ADN, 5% water and 3% by-products mainly composed of 2-cyanoethyladiponitrile and PN. The catholyte tank 2 as shown on the flow sheet of FIG. 1 was used alone. A portion of the electrolyte was not passed to the separation column 8 but directly to the water stripper 10 in which low-boiling substances such as AN, PN and water was distilled off. The residual liquid was then cooled, to which were added ADN at 100 ml./hr. and sodium hydroxide. The mixture was allowed to stand in the separation column 8 for separation. The aqueous phase separated, pH 10, was neutralized with phosphoric acid prior to returning to the catholyte tank 2. A portion of the oil phase was passed to the purification step and the balance to the extraction column 28 filled with Raschig rings. Thus, alkali value of the electrolyte in the electrolyzer was maintained below 20. In the extraction column 28, countercurrent extraction was made between the aqueous phosphoric acid solution of pH=2.5 and the oily layer at the ratio by volume of 1:5. The resulting oily layer was passed to the catholyte tank 2 while the aqueous phosphoric acid was contacted with PN for recovery of ADN therefrom, and then discarded. Results of a 360 hours' continuous operation conducted under the same experimental conditions as in Example 1 except for the above and those without the above-mentioned treatment were compared with reference to the yields of ADN and PN on the basis of the AN consumed.

	With treatment		Without treatment	
	ADN	PN	ADN	PN
50 hours.....	78	15	75	15
360 hours.....	75	17	58	35

The agglutinates on the surface of the cathode on completion of the electrolysis amounted to less than $\frac{1}{20}$ as much as those produced in the electrolysis without the treatment.

Example 7

An electrolysis was conducted in the same way as in Example 1 except that 20% sodium sulfate was used as the electrolytic supporting salt. Comparison was made of 300 hours' continuous operation with that without the treatment with reference to the yields of ADN and PN on the basis of the AN consumed to give the results shown

below. The electrolysis without treatment could be operated at longest for 300 hours due to much hydrogen gas evolved by the agglutinates on the surface of the cathode.

5	With treatment		Without treatment	
	ADN	PN	ADN	PN
50 hours.....	70	26	68	28
300 hours.....	70	27	38	68

The surface of the cathode on completion of the electrolysis had agglutinates adhered in amount about $\frac{1}{10}$ as much as that obtained when the electrolysis was carried out without the above treatment.

Example 8

An electrolysis was conducted as in Example 1 in which the aqueous layer separated was placed in a separate tank and mixed with ADN added at a rate of 200 ml./hr. The mixture was then passed to a separation column separately set up. The ADN phase was purified in the purification step by distillation for use in recycling. The aqueous phase was passed to the water stripper 10. Results are shown below.

	ADN	PN
500 hours.....	91	6.9
1,500 hours.....	92	6.1

The amount of agglutinates on the surface of the cathode on completion of the electrolysis was about $\frac{1}{5}$ as much as that in Example 1.

Example 9

An electrolysis was conducted as in Example 3 in which the aqueous phase separated was placed in a tank and thoroughly mixed with ADN added at a rate of 200 ml./hr. The mixture was separated in a separation device (Coalescer) and into an aqueous layer and ADN layer, which latter was passed to the purification step in which it was purified by distillation for re-use. The aqueous phase was neutralized with aqueous sulfuric acid and then passed to the water stripper. Results are shown below.

	ADN	PN
450 hours.....	92	6.0
1,500 hours.....	91	6.5

The amount of agglutinates on the surface of the electrode on completion of the electrolysis was about $\frac{1}{4}$ as much as that in Example 3.

We claim:

1. In the process for electrolytically hydrodimerizing acrylonitrile, improvement which comprises separating an electrolyte effluent containing an electrolytic supporting salt, acrylonitrile, adiponitrile and electrode reaction-impairing materials into oily and aqueous layers, removing the electrode reaction-impairing materials contained in the oily layer and recycling the resulting oily layer thus purified to the electrolyte.
2. Method according to claim 1 wherein a homogeneous aqueous solution is used as the electrolyte.
3. Method according to claim 1 wherein an emulsion is used as the electrolyte.
4. Method according to claim 1 wherein adiponitrile is added to said electrolyte to effect separation thereof into oily and aqueous layers.
5. Method according to claim 4 wherein additional adiponitrile is added to said separated aqueous layer to transfer electrode reaction-impairing materials contained in said aqueous phase into an adiponitrile phase and the adiponitrile layer thus containing the electrode reaction-impairing materials is purified by distillation.
6. Method according to claim 1 wherein pH of the separated aqueous layer is from 5 to 7.

11

7. Method according to claim 1 wherein said separated oily layer is contacted with a cation exchange resin thereby adsorbing thereon said electrode reaction-impairing materials.

8. Method according to claim 1 wherein said separated oily layer is contacted with an aqueous acid solution thereby transferring electrode reaction-impairing materials into the aqueous acid solution for removal of the same.

9. Method according to claim 1 wherein rate of said only phase treated is from 0.5 ml. to 50 ml./a·hr.

10. Method according to claim 7 wherein said cation exchange resin is of H-form or the form of cation of the electrolytic supporting salt.

11. Method according to claim 7 wherein rate of the cation exchange resin used is from 0.003 to 2 ml./a·hr. 15

12. Method according to claim 8 wherein pH of said aqueous acid solution is from 5 to 1.

12

13. Method according to claim 8 wherein amount of the aqueous acid solution for the extraction is from 0.5 to 50 times as much as that of the oily layer to be treated.
